ATTORNEYS

UNITED STATES PATENT OFFICE.

COLLIS H. STEERE, OF PALO ALTO, CALIFORNIA.

DESIGN FOR A CANDY-CONTAINER.

58,165.

Specification for Design.

Patented June 14, 1921.

Application filed December 18, 1919. Serial No. 345,899. Term of patent 3½ years.

To all whom it may concern:

Be it known that I, COLLIS H. STEERE, a citizen of the United States, residing in the city of Palo Alto, county of Santa Clara, and State of California, have invented a new, original, and ornamental Design for a Candy-Container, of which the following is a specification, reference being had to the accompanying drawings, forming part thereof.

Figure 1 is a plan view of the candy container.

Fig. 2 is a central vertical section on the line 2—2 of Fig. 1.

I claim:

The ornamental design for a candy container, as shown.

COLLIS H. STEERE.
